CLAIM

The ornamental design for a hair coloring easel, as shown and described.

DESCRIPTION

FIG. 1 is a perspective view of the top, front and left side of a hair coloring easel showing my new design;

FIG. 2 is a right side elevational view thereof, the side opposite being a mirror image of the side shown; and,

FIG. 3 is a rear elevational view thereof.

The bottom surface of the easel forms no part of the claimed design.

The undisclosed surfaces of the upper platform and central rectangular compartment follow the contours of the sides shown.
